DiversiTech Product Catalog product subcategory for Drain Pans; <http://www.diversitech.com/Product-Sub-Category>; Aug. 14, 2012.*Primary Examiner* — Susan E Krakower*Assistant Examiner* — Lisa A Grabenstetter(74) *Attorney, Agent, or Firm* — Nelson Mullins Riley & Scarborough, LLP(57) **CLAIM**

The ornamental design for an air conditioning system drain pan, substantially as shown and described.

DESCRIPTION

FIG. 1 is a perspective view of an air conditioning system drain pan showing my new design;

FIG. 2 is an exploded perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front view thereof; and,

FIG. 8 is a rear view thereof.

The broken lines in FIG. 2 show the relationship of hardware to the air conditioning system drain pan only and form no part of the claimed design.
